UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

1,091,347.

Specification of Letters Patent. Patented Mar. 24, 1914.

Application filed March 27, 1913. Serial No. 757,104.

To all whom it may concern:

Be it known that I, DAVID S. KENNEDY, a citizen of the United States, residing at Brooklyn, in the county of Kings and State 5 of New York, have invented certain new and useful Improvements in Typographical Machines, of which the following is a specification, reference being had therein to the accompanying drawing.

10 My invention relates to typographical machines, such as linotype machines of the general organization represented in Letters Patent of the United States, No. 436,532, to O. Mergenthaler, wherein circulating mat- 15 rices are released from a magazine in the order in which their characters are to appear in print and then assembled in line, the composed line transferred to the face of a mold, the mold filled with molten metal to 20 form a slug or linotype against the matrices which produce the type characters thereon, and the matrices thereafter elevated and re- turned through a distributing mechanism to the magazine from which they started. 25 More particularly, it refers to machines of this type when equipped with a plurality of magazines, any one of which may be brought into action at will, and with a single dis- tributing mechanism arranged to deliver 30 matrices into the selected magazine. In such machines, it is essential that all the matrices be returned to the magazine to which they belong before another is brought into action; and the object of this invention 35 is to arrest the distributing mechanism as soon as the operator starts to make the change. In this way, not only is the dis- tribution of matrices prevented while the change is being made, but also, when the 40 operator leaves his place at the keyboard to re-start the distributing mechanism, he is necessarily forced to observe its condition and note whether or not matrices are pres- 45 ent therein, in which event he may remove them and thus obviate their delivery to an improper magazine.

I have shown my invention in preferred form and by way of example, and as applied to a type of machine wherein two magazines 50 are movable relatively to the distributing mechanism, as presented for instance in my application for Letters Patent, Serial No. 745,609, filed February 1, 1913. However, as will readily appear, it is equally applica- 55 ble to other styles of machines wherein a

larger number of magazines or even a single magazine is employed, or also in connec- 60 tion with machines wherein the magazines are stationary and the other operative parts are movable relatively thereto. Further, it 65 may be applied to other kinds of typographical machines, such as those which handle type or dies instead of matrices. These and many other variations in the ap- 70 plication of my improvements, as well as in 75 their particular embodiment, may be made and will still be comprised within the spirit of my invention. Generally speaking, I 80 desire it to be understood that I do not limit myself to any specific form or embodi- 85 ment, except in so far as such limitations are specified in the claims.

Referring to the drawings: Figure 1 is a side view of a portion of a linotype machine, with my invention applied thereto, showing the distributing mechanism, the magazine entrance, the upper ends of the magazine, etc.; Fig. 2 is a similar view, but with the parts in different position; Fig. 3 is a sec- 90 tional detail, taken substantially on the line 3-3 in Fig. 2; Fig. 4 is a detached perspective view, illustrating the action of the stop devices; and Fig. 5 is a perspective view of a modification.

The matrices X are, as usual, conveyed 95 along the distributor rail A by the rotating screws A¹ and pass therefrom through the magazine entrance B into the magazine C. In the present instance, I have shown two such magazines, either one of which may be 100 brought into action, substantially in the manner set forth in my previously men- 105 tioned application. The entrance B is piv- 110 otally connected to the frame at B¹, and is held against the force of gravity and in op- erative relation to the other parts by the spring B².

The parts so far described, and their mode 115 of operation, constitute in themselves no part of my present invention and are or may be substantially similar to those well known in the art.

For the reasons previously indicated, it is 120 desirable and necessary to arrest the dis- tributing mechanism when the magazines are shifted, and this end I attain specifically 125 through the magazine entrance and a fur- ther modification whereby the entrance is moved from its normal position when the shifting action begins. To that end, the bar 130

C¹, which is connected to and moves with the magazines, is provided with a plate D formed with recesses or notches D¹ corresponding in number and location to the several magazines; and attached to the pivotally mounted throat B is a projecting member E designed to engage with one or another of the said notches D¹, according to the particular magazine in action, all as illustrated in Fig. 1. When the magazines are shifted, the plate D is moved therewith and relatively to the throat B, thereby disengaging the projecting member E from the notch D¹, and swinging the entrance B about its pivot B¹ and against the force of the spring B², as indicated in Fig. 2. It is this pivotal movement of the entrance that I avail myself of to arrest the distributing mechanism, and in a manner substantially similar to that disclosed in Letters Patent of the United States to John R. Rogers, No. 798,298.

Connected to the entrance B is the bar F, which normally engages with the piece G and holds it inwardly against the force of the spring H. When the spring is permitted to act, it elevates the arm J and moves the stop pin K into the path of the rotating side cam L, thereby arresting the distributing mechanism, all in the manner set forth in the said Rogers patent. When the throat B is swung outwardly by the shifting of the magazines, in the manner previously described, the bar F releases the piece G, the distributing mechanism comes to rest, and in this way the further delivery of undistributed matrices is prevented. Before the operator re-starts the distributing mechanism, he removes such matrices therefrom and thereby avoids their delivery into an improper magazine.

In Fig. 5, I have illustrated a modification wherein the spring B², which holds the throat B in position, is connected to the pivoted arm M, which at one end is engaged by the spring-pressed trigger N, the said trigger being so located as to be acted upon and held by one or another of the pins O carried by the magazine base frames C¹⁰, according to the magazine in operative position. When the shifting action begins, the pin O is moved out of engagement with the trigger N, which thereupon releases the arm M and thus relieves the tension of the spring B²; whereupon the throat B moves by gravity about its pivotal point B¹ and effects the stoppage of the distributor, in the manner previously described. The arm M is provided with a setting handle M¹, whereby the throat B may be restored to operative position and the arm M be again brought into engaged relation to the trigger N, when another magazine comes into action.

As previously stated, I have shown my

invention only in preferred form and by way of example, and many changes and variations therein will suggest themselves to those skilled in the art without departure from its scope.

Having thus described my invention, its construction and mode of operation, what I claim and desire to secure by Letters Patent of the United States is as follows:

1. In a typographical machine, the combination of a movable magazine, distributing mechanism therefor, and means whereby the movement of the magazine automatically arrests the operation of the distributing mechanism and thus prevents the distribution of matrices to an improper magazine.

2. In a typographical machine, the combination of a plurality of magazines capable of independent use, distributing mechanism to deliver type or matrices to the magazine in use, and means whereby the mechanical selection of a different magazine automatically arrests the operation of the distributing mechanism and thus prevents the distribution of matrices to an improper magazine.

3. In a typographical machine, the combination of a plurality of magazines movable as a whole to bring one or another into operative position, distributing mechanism to deliver type or matrices to the selected magazine, and means whereby the movement of the magazines automatically arrests the operation of the distributing mechanism and thus prevents the distribution of matrices to an improper magazine.

4. In a typographical machine, the combination of a movable magazine, and distributor stop mechanism operated automatically by the movement of the magazine; whereby the distribution of matrices to an improper magazine will be prevented.

5. In a typographical machine, the combination of a plurality of magazines movable as a whole to bring one or another into operative position, distributing mechanism to deliver type or matrices to the selected magazine, and means whereby the movement of the magazines automatically prevents the delivery of any undistributed type or matrices to another magazine when it is brought into operative position.

6. In a typographical machine, the combination of a movable magazine for the type or matrices, an entrance therefor, distributing mechanism to deliver the type or matrices to said entrance, and means whereby the movement of the magazine automatically prevents such delivery of the type or matrices and their consequent distribution to an improper magazine.

7. In a typographical machine, the combination of a movable magazine for the type or matrices, an entrance therefor adapt-

ed to be moved automatically from its normal position by the movement of the magazine, and distributor stop mechanism adapted to be operated by the movement of the entrance; whereby the distribution of matrices to an improper magazine will be prevented.

In testimony whereof I have affixed my signature in presence of two witnesses.
